Primary Examiner — Natasha Vujcic

(57) **CLAIM**

We claim, The ornamental design for a cigarette filter, as shown and described.

DESCRIPTION

1.-2. Cigarette filter

3.-4. Front part of cigarette filter

1.1 : Perspective

1.2 : Perspective

1.3 : Front

2.1 : Perspective

2.2 : Perspective

2.3 : Front

3.1 : Perspective

3.2 : Front

4.1 : Perspective

4.2 : Front

Designs 1 and 2 relate to a cigarette filter and designs 3 and 4 relate to a front side of a cigarette filter; the designs show the shape of an air opening provided in an end cap of the cigarette filter; for designs 1 and 3, the shape of the air opening resembles to a flower with six petals; for designs 2 and 4, the shape of the air opening resembles to a leaf with seven regularly arranged lobes.

The broken lines in the drawings illustrate portions of the cigarette filter which forms no part of the claimed design.
